EDWARD P. DONNELLAN, OF BROOKLYN, NEW YORK, ASSIGNOR TO STANDARD-JOHNSON COMPANY, INC., OF BROOKLYN, NEW YORK, A CORPORATION OF NEW YORK

COIN SEPARATING AND COUNTING MECHANISM

Application filed May 11, 1928. Serial No. 276,853.

This invention relates to machines for separating and counting coins; and the invention has reference, more particularly, to a novel construction of machine adapted to both separate and count coins of mixed denominations by a single operation and by substantially a single instrumentality, in connection with which both the functions of sorting and counting are continuously carried on in a substantially simultaneous manner.

The present invention has for its principal object to provide in connection with coin separating or assorting drop-out discharge openings of a coin separator, having an inclined movable recessed conveyor plate to deliver the coins to said discharge openings, a novel construction and arrangement of means with which the discharged coins engage in passing, whereby the same are caused to actuate registers or counters so that the several denominations of coins are counted while they are being assorted or separated. To this end the instant invention provides a relatively simple, compact and easily operated unitary mechanism whereby the operations of assorting and counting mixed coin may be rapidly and continuously carried on.

Other objects of this invention, not at this time more particularly enumerated, will be clearly understood from the following detailed description of the same.

The invention is illustrated in the accompanying drawings, in which:—

Fig. 1 is in part a side elevation and in part a vertical section on line 1—1 in Fig. 4 of the novel coin assorting and counting machine of this invention; Fig. 2 is a fragmentary view of a modified power transmission means which may be utilized to move the coins in actuating relation to the counting means; Fig. 3 is a fragmentary section on line 3—3 in Fig. 2; Fig. 4 is a bottom plan view of the mechanism; Fig. 5 is a developed section through the outer discharge openings of the machine showing the coin actuated counting mechanism for the different denominations of coin, said view being generally on line 5—5 of Fig. 4; Fig. 6

is a fragmentary enlarged section on line 6—6 in Fig. 1; and Fig. 7 is a transverse section on line 7—7 in Fig. 6.

Similar characters of reference are employed in all of the above described views, to indicate corresponding parts.

Referring to the drawings, the reference character 10 indicates a bed-plate which is mounted on supporting standards 11 preferably in such manner as to be inclined at an angle of approximately forty-five degrees. Said bed-plate 10 is preferably of circular shape and is provided at its under side with a central bearing hub 12. Journaled in said bearing hub 12 is a spindle 13, upon the upper end of which is fixed, so as to be rotated thereby, a carrier or conveyor 14, which lies contiguous to the upper surface of said bed-plate so as to be rotatably slidably thereover. The means for rotating said spindle 13 and carrier or conveyor plate 14 comprises a drive shaft 15 suitably mounted in bearings 16 and adapted to be driven either by hand or from any suitable source of power such as an electric motor (not shown). Fixed on said drive shaft 15 is a drive worm 17 which meshes with and drives a worm gear 18 rigidly connected with said spindle 13. The carrier or conveyor plate 14 is provided with suitably disposed annular rows of open coin carrying or propelling recesses or pockets, which, in the form and arrangement illustrated in the accompanying drawings, comprise an outer row of recesses or pockets 19 of a diameter

slightly in excess of the size of the largest coin, viz the half-dollar, and an inner row of recesses or pockets 20 of somewhat smaller diameter, the same preferably being slightly in excess of the size of a quarter-dollar.

When thus arranged the outer row of recesses or pockets 19 will receive and convey all sizes of coins from a dime to a half-dollar inclusive, and the inner row of recesses or pockets will only receive and convey the sizes of coins from a dime to a quarter-dollar inclusive.

The up-tilted end portion of the bed-plate 10 is provided with an outer row of drop-out discharge openings progressively graded in width to respectively pass coins of the size of dimes, pennies, nickles, quarters and half-

100

dollars, said openings being respectively indicated by the reference characters 21, 22, 23, 24 and 25; said outer row of drop-out discharge openings is aligned with the outer row of recesses or pockets 19 of the carrier or conveyer plate 14. Inwardly spaced from said outer row of drop-out discharge openings is an inner row of similar drop-out discharge openings formed in said bed plate 10 and progressively graded in width to respectively pass coins of the size of dimes, pennies, nickels and quarters, said openings being respectively designated by the reference characters 21', 22', 23' and 24'; said inner row of drop-out discharge openings is aligned with the inner row of recesses or pockets 20 of the carrier or conveyer plate 14. Secured to the lower or down-tilted end of said bed-plate 10, and at the upward face thereof, is a substantially semi-circular receiving hopper 26 to surround the lower moving end or side of the carrier or conveyer plate 14, the same serving to receive and hold a mass of mixed coins subject to the picking-up action of the recesses or pockets of the carrier or conveyer plate 14, which serves to successively deliver the mixed coins to and over the discharge drop-out openings whereby the same are separated according to their respective denominations.

Connected with the underside of the bottom plate 10 to underlie each discharge drop-out opening thereof is a runway or chute 27 so shaped as to turn the coins entering or dropping into the same from initial horizontal or flat disposition to vertical or edgewise disposition as the coins move therethrough to the free end thereof for discharge therefrom. Connected with each set of runways or chutes 27 which serve a given denomination of coin are bearing members 28 to journal radial shafts 29 transversely disposed adjacent to the discharge mouth of the runways or chutes. These shafts 29 may be rotated from the central spindle 13 in a suitable manner. For example, the lower end of said spindle 13 may be provided with a bevel drive gear 30 which meshes with pinions 31 fixed on the respective shafts 29, as shown in Figs. 1 and 4; or the shafts 29 may be journaled in spring-pressed bearings 28' and said spindle 13 may be provided with a friction drive disc 30' which cooperates with friction rollers 31' fixed on the respective shafts 29, in the manner indicated in Figs. 2 and 3 of the drawings; or any other suitable means for driving said shafts 29 may be employed. Fixed on each shaft 29 to enter the runways or chutes 27 served thereby at one side of the latter are rollers 32. The walls of said chutes or runways 27 are cut away to permit the said rollers 32 to lie in and at one side of the path of movement of said coins descending through said chutes or runways 27. The side of each runway or chute 27 which is opposed to the roller cooperating therewith is cut

away to receive a trip lever mechanism to be actuated by coins engaged by said roller when descending through the chute or runway and prior to ejection therefrom. The trip lever mechanism comprises suitable bearing brackets 33 associated with each set of runways or chutes 27 which serve a given denomination of coin. Mounted in said bearing brackets 33 are rock-shafts 34, and fixed on said rock-shafts 34 are trip levers 35 which extend downwardly in opposition to the corresponding rollers 32. These trip levers 35 are preferably inwardly curved or inclined so that their free ends are spaced from the opposed rollers 32 for a distance less than the diameter of a given coin to be served by the particular runways with which said rollers and trip levers are associated. Connected with each rock-shaft 34 is a suitably attached spring means 36 for yieldably holding the trip-levers 35 in normal inwardly swung positions. Connected with the runway or chute structure serving each denomination of coin is a supporting shelf 37 upon which is mounted a coin register or counter device 38 having any well known arrangement of counting wheels and an actuating lever 39 by means of which counting wheel mechanism is actuated. Fixed on each rock-shaft 34 is a trip finger 40 to engage and operate the actuating levers 39 of the respective corresponding register or counter devices, whenever a coin descends a given runway or chute 27 and is thrust, in passing into actuating relation to the trip lever 35 by a corresponding roller 32.

In the operation of coin separator and counting mechanism constructed as above described, a quantity of mixed coins are dumped into the hopper 26 and upon the rotating carrier or conveyer plate 14. The rotation of the carrier or conveyer plate 14 will convey upward all coins engaged in the recesses 19 and 20, whereby the coins are carried to and are caused to move flat-wise over the drop-out discharge openings 21 and 25 inclusive and 21' to 24' inclusive, whereupon the coins will drop downwardly out of the recesses when the latter register over a drop-out discharge opening sized to accommodate their particular diameters. The coins will thus be delivered by the drop-out discharge openings into the proper chutes or runways 27 assigned to their particular denominations. Each coin in descending its proper chute or runway 27 will first be turned from its horizontal or flat to a vertical or edgewise position ere it arrives at the lower end of the chute or runway, and consequently will be presented for edgewise passage between the roller 32 and trip lever 35 of the particular chute or runway traversed thereby. The moment a coin engages between a roller 32 and an opposed trip-lever 35, the rotation of the former (as continuously driven by the trans-

mission means intermediate its shaft and the main spindle 13 of the machine) will force the coin downwardly against the yieldable trip-lever 35, thereby causing the latter to swing outwardly against the tension of the spring means 36 thus rocking the connected rock-shaft 34 and at the same time swinging the trip-finger 40 of said shaft into operating engagement with the actuating lever 39 of the particular register or counter device corresponding to the runway or chute through which the coin thus passes, with the result that as each coin passes through its proper runway or chute it is counted or registered by a proper registering or counting device. It will thus be apparent that the coins passed continuously through the machine will be both separated according to their several denominations and a separate count 20 of each denomination recorded all in a substantially simultaneous manner. It will also be obvious that the mechanism is exceedingly compact, and of a comparatively simple character, while being so designed as to be operated from a single power source, whether manual or mechanical.

If desired suitable receptacles R in the form of cans or boxes may be placed beneath the discharge end of the runways or chutes 30 respectively serving different denominations of coins, or any other suitable, convenient or well known means may be provided for the reception of coins which by the operation of the driven rollers 32 are ejected from the runways or chutes after having been propelled past and in operating engagement with the trip lever mechanisms serving said runways or chutes and corresponding coin register or counting devices.

40 In the accompanying drawings I have shown my invention and have described the same in the above specification merely in preferred form and by way of example, but obviously many alterations and variations may 45 be made therein and in its mode of application, which will still be comprised within its spirit. Generally speaking, I desire it to be understood that I do not limit myself to any specific form or embodiment, except in so far 50 as is specified in the here-following claims.

I claim:—

1. In a machine of the kind described, a counting register, a pivoted trip lever for actuating the same, an impeller roller opposed to said trip lever, said trip lever having a curved free end portion normally converging upon said roller, and means for guiding coins edgewise between said trip lever and roller, whereby said roller rotates a coin in rolling contact with and past said trip lever to effect register actuating movement of the latter.

2. In a machine of the kind described, a counting register having an actuating lever, a pivoted trip lever having a finger to operatively engage said register actuating lever,

an impeller roller opposed to said trip lever, said trip lever having a curved free end portion, spring means for turning said trip lever to normal initial position with its free curved end portion converging on the periphery of said roller, and means for guiding coins edgewise between said trip lever and roller, whereby said roller rotates a coin in rolling contact with and past said trip lever to effect register operating movement thereof.

3. In a machine of the kind described, coin runways for coins of various denominations, driven impeller rollers, said rollers being respectively mounted relative to said runways so that their peripheries are exposed at sides of the latter for engagement by coins entered in the same, said runways being of such cross-sectional shape as to present coins edgewise to the peripheries of said rollers, pivoted trip levers having curved free end portions bounding said runways in opposition to said rollers, said trip levers having spring means to urge their free curved ends into positions converging on said rollers, said rollers being adapted to urge coins entered in said runways into rolling contact with the free curved ends of said trip levers to turn the latter on their pivots and at the same time eject said coins from said runways, counting registers, and means actuated by turning movement of said trip levers for operating said counting registers.

In testimony, that I claim the invention set forth above I have hereunto set my hand this 2nd day of May, 1928.

EDWARD P. DONNELLAN.
